FRANK A. COOK, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 926,050.

Specification of Letters Patent. Patented June 22, 1909.

Application filed February 16, 1909. Serial No. 478,143.

To all whom it may concern:

Be it known that I, FRANK A. COOK, a citizen of the United States, residing in Hartford, in the county of Hartford and 5 State of Connecticut, have invented certain new and useful Improvements in Type-Writing Machines, of which the following is a specification.

This invention relates to the ribbon mechanism of front strike writing machines of the kind in which either one or another color of ribbon can be used at will.

The principal object of the present invention is to provide a simple device readily applicable to existing machines of this kind, for rendering the ribbon inactive at the type strokes, so that the types may strike off the ribbon as when writing stencils.

The improvement is shown in connection 20 with a bichrome ribbon mechanism, in which two fields of color are united in a single ribbon, and in which two keys are provided, one for each color of ribbon, so that upon depressing either key the corresponding 25 color or field of ribbon is caused to cover the printing point at the type strokes. In addition to said keys, I provide a lever which is normally in idle position, but may be 30 swung to a position to disconnect or disable the ribbon-vibrating devices, so as to enable 35 the types to write off from the ribbon. The lever is shown in connection with a cross-arm bearing the two color keys and having a projection which is engageable by a cam notch formed upon the lever, for the purpose specified.

It will be seen that although a single ribbon is shown, the device is also applicable to machines in which two ribbons are controlled by similar keys or equivalent devices.

In the accompanying drawings, Figure 1 is a perspective rear view of the present improvement applied to an Underwood front strike writing machine; the ribbon-vibrating 45 mechanism being shown as ineffective at the type strokes, the type being in printing position above the ribbon. Fig. 2 is a sectional

rear elevation showing one color key depressed. Fig. 3 is a similar view showing the other color key depressed. In Figs. 2 50 and 3 the auxiliary lever is shown in idle position. Fig. 4 is a sectional side elevation of the ribbon actuator and the connected lever and ribbon-vibrator; the parts shown in normal positions. 55

Color fields 1 and 2 are united edge to edge, to form a single ribbon through which types 3 strike rearwardly against a platen, not shown. The ribbon is threaded through a vibrator 4, which is operated by a lever 5, 60 the latter pivoted at 6 upon a bracket 7 secured to a shift rail 8 of the case-shifting mechanism in said machine. A universal bar 9, vibrated by the type-bars, is fixed upon a frame 10. Carried upon said frame 65 10 is an actuator 11 having one vertical slot 12 to engage a wrist 13 on the lever 5, and an opposite vertical slot 14 to engage a wrist 15 provided upon said lever 5 nearer to the fulcrum 6 of the lever. Said slots are 70 formed in ears bent forwardly from the body of the actuator, and the latter is adjustable to bring either slot into engagement with its associated wrist, such adjustment being effected by a link 17 pivoted at 75 18 to the actuator, and the latter being held by a screw 19 upon a bracket 20 fixed upon said universal bar frame 10; a vertical wall of said bracket having a horizontal slot 21 through which said screw extends, the slot 80 permitting the required adjustment of the actuator.

When the slot 12 is in engagement with wrist 13, the lever 5 is given a short stroke, and the upper field or color band 1 is caused 85 to cover the printing point at the type strokes. When, however, the actuator is shifted to bring the slot 14 into engagement with the wrist 15, the lever 5 is given a greater stroke at the type strokes, and hence 90 the lower color band or field 2 is caused to cover the printing point at the type strokes. For effecting this adjustment of the actuator, the link 17 is connected to an arm 22 fixed

upon a rock-shaft 23, the latter carrying at its forward end a cross-arm 24 having keys 25, 26, corresponding to the color bands 1, 2; so that upon depression of either key, the corresponding color band is brought into use. A yielding detent 27 is caused to engage the beveled end of a pin 28 projecting rearwardly from the arm 24, to hold said arm in either the Fig. 2 or the Fig. 3 position, to cause either the color band 2 or the color band 1 to cover the printing point at the type strokes; said detent 27 being incapable of holding the train 24, 23, 22, 17, 11 in a midway position.

15 Upon a bracket 29, forming part of or secured to the framework 30 of the machine, is pivoted, at its lower end, at 31, a lever 32 having a handle or finger-piece 33 at its upper end. Between its ends it is provided 20 with a transverse slot 34 whose open end terminates in opposite cams 35, 36, so constructed that when the lever is moved from the right from either Fig. 2 position or the Fig. 3 position, the projection 28 is engaged 25 by one of said cams, and the key-bearing cross-lever 24 is brought to a horizontal position, as at Fig. 1; the entire train of devices from 24 to 11 thus being brought to a position midway between their extreme positions; and both wrists 13 and 15 being out 30 of engagement with the slotted actuator, so that the latter, although reciprocating at the key strokes, has no effect upon the ribbon-vibrating lever 5, and hence the ribbon 35 is silenced and the type strikes above the ribbon, as at Fig. 1.

The lever 32 is provided with a yielding detent or tooth 37 normally engaging a notch 38 formed in the bracket 29; but upon moving the lever over to the effective Fig. 1 position, said detent engages a notch 39 in said bracket, whereby the described train of mechanism is mechanically held in ribbon-silencing position. The sides of the slot 34 are of such shape as to lock the key-bearing cross-lever 24 against movement while said lever is in the Fig. 1 position; the cams forming together with the sides of said slot a pair of jaws for controlling the position of 50 the described train of devices.

At Fig. 1 the detent 27 is resting idly upon the tip of the projection 28.

Variations may be resorted to within the scope of the invention.

55 Having thus described my invention, I claim:

1. In a typewriting machine, the combination with an actuator which reciprocates at the type strokes, of key-controlled mechanism movable to two positions to cause said actuator to vibrate either of two fields of ribbon to cover the printing point at the type strokes, a yielding detent to hold said key-controlled mechanism in either of said 60 positions, and an independently operable

locking device having a finger-piece and provided with means to move said key-controlled mechanism to and lock it in an intermediate position to render said actuator ineffective.

2. In a typewriting machine, the combination with an actuator which reciprocates at the type strokes, of key-controlled mechanism movable to two positions to cause said actuator to vibrate either of two fields of ribbon to cover the printing point at the type strokes, a yielding detent to hold said key-controlled mechanism in either of said positions, an independently operable locking device having a finger-piece and provided with means to move said key-controlled mechanism to and lock it in an intermediate position to render said actuator ineffective, and means to detain said locking device in effective position.

3. In a typewriting machine, the combination with an actuator which reciprocates at the type strokes, of a key-controlled train including a rocking device movable to two positions and connected to means to cause said actuator to vibrate either of two fields of ribbon to cover the printing point at the type strokes, a yielding detent connected to said train, and a lever having a slot or pair of jaws and movable to a position to cause said slot or jaws to engage a projection on said rocking device to move said train to an intermediate position, and render said actuator ineffective at the type strokes.

4. In a typewriting machine, the combination with an actuator which reciprocates at the type strokes, of a key-controlled train including a device movable to two positions and connected to means to cause said actuator to vibrate either of two fields of ribbon to cover the printing point at the type strokes, and cams to move said device from either such position to an intermediate position whereby the actuator is rendered ineffective.

5. In a typewriting machine, the combination with an actuator which reciprocates at the type strokes, of a rock shaft having key-bearing arms and connected to means to cause said actuator to vibrate either of two fields of ribbon to cover the printing point at the type strokes, a yielding detent to hold said rock shaft in either of such positions, and a lever having cams to engage a projection on one of said arms to force said rock shaft from either of such positions to an intermediate position, whereby the actuator is rendered ineffective.

6. In a typewriting machine, the combination with an actuator which reciprocates at the type strokes, of mechanism to cause said actuator to vibrate either of two ribbon fields to cover the printing point at the type strokes, keys to control said mechanism, and a lever distinct from said mechanism and

having means to render said actuator ineffective and lock said keys against movement.

7. In a typewriting machine, the combination with an actuator which reciprocates at the type strokes, of mechanism to cause said actuator to vibrate either of two ribbon fields to cover the printing point at the type strokes, keys to control said mechanism, a

lever distinct from said mechanism and having means to render said actuator ineffective and lock said keys in idle positions, and means for holding said lever in effective position. 10
